PRICE TICKET

James William Hutt, Toronto, Ontario, Canada

Application May 17, 1935, Serial No. 21,998

4 Claims. (Cl. 40—20)

The invention appertains to a ticket or tag structure applied to textile goods and/or articles made therefrom. The invention more particularly concerns a ticket or tag structure of the pinless class for use on sheer goods or articles on which a pin ticket would be objectionable due to the likelihood of its use resulting in injury to the fabric through the attaching pin piercing it.

The present invention provides an efficient and serviceable attaching means for a price ticket or the like which does not pierce or otherwise damage the textile fabric to which it is applied. This renders it particularly suitable for use upon sheer hosiery to which it may be very readily applied.

The invention consists essentially of a ticket body of pasteboard foldable upon itself and having one of its ends supplied with a transverse slot and the other end fitted with an upstanding wire loop or the like. In applying the ticket it is placed over the edge of the article and the ends pressed together so as to cause the wire loop to enter the slot with the material of the article thereover. The slot is preferably shaped to compose opposing lips that interlock with the loop and thus secure the ticket.

Referring to the accompanying drawing, Figure 1 is a perspective view of the ticket spread out flat.

Figure 2 is an edge view thereof showing the body folded at right angles.

Figure 3 is a left-hand view of Figure 2.

Figure 4 is a longitudinal section of the ticket completely folded and showing the manner in which the ends interlock.

Figure 5 is a plan view of the ticket attached to goods.

Figure 6 is a section along line 6—6 of Figure 5.

Like numerals of reference indicate corresponding parts in each of the figures throughout the drawing of the invention.

The drawing is illustrative of the preferred form of the invention, and shows an elongated ticket body 8 of suitable material such as the usual pasteboard. The body is creased or otherwise prepared for folding about a transverse bend line 9 located slightly nearer the end 10 so that when the other end 11 is folded over, it will project or overhang as seen in Figures 4 and 6.

The end 10 has a fastening element 12 secured to it comprising a substantially U-shaped wire having its ends 13 extending longitudinally of the body inwardly of the edge 14 with the extremities 15 forced through the material of the body and clinched on the inner face 16. This stapling of ends firmly secures the fastening element, and

is performed by a machine common to the pin-ticket industry. The bight 17 is semi-circular and bent at right angles to the ends 13 and the plane of the end 10 so as to upstand from the inner face 16.

The other end 11 of the body has a transverse slot 18 adapted to register with the bight 17 in the folding of the body. The opposing side edges of the slot are curved away from each other as at 19 on an arc of a circle and are spaced apart a distance less than the diameter of the wire forming the bight. Said curved edges compose lips for gripping the textile material.

To attach the ticket, the end 10 is placed under the edge portion of the goods 20 and the other end is folded over the goods and pressed down so that its slot 18 will engage and receive the bight 17 of the fastening element. The lips are thus forced under the loop or bight and grip the goods thereover. It has been demonstrated that this mode of attaching the ticket does not injure the goods and yet secures an excellent grip upon them that does not yield in their customary handling.

What I claim is:

1. A ticket of the class described composed of a body adapted to be folded upon itself so as to bring one part into overlying relation with the other part, and interlocking attaching means incorporated therewith consisting of a U-shaped wire having its ends stapled to one of said parts and its bight bent at right angles to the inner face thereof, and opposing pliant lips provided on the other of said parts of the body receptive to said bight.

2. A ticket of the class described composed of a body adapted to be folded upon itself so as to bring one part into overlying relation with the other part, one of said parts having a transverse slot of which the side edges recede in an arc of a circle to compose lips approximating each other, and an upstanding wire loop rigidly attached to the other of said parts of the body adapted to be forced in the slot so that the lips will snap past the bight portion of the loop.

3. A ticket of the class described composed of an elongated pasteboard body having a bend line transversely of its length and nearer one end than the other, said body being foldable about the bend line so that one end will project beyond the edge of the other, the projecting end having a transverse slot of which the sides recede on an arc of a circle to present lips approximating each other, a U-shaped wire having a semi-circular bight bent at right angles to its ends and disposed

perpendicularly at the edge of the end of the body opposite the slotted end aforesaid, said wire having its ends stapled to the body, the bight being adapted to be forced into the slot so that the lips thereof will engage under it.

4. A ticket for textile fabric, said ticket consisting of a pasteboard body adapted to be folded upon itself so as to bring one part into overlying relation with the other part, one of said parts having an elongated slot of which the op-

posing side edges protrude forwardly towards each other from substantially the ends of the slot, the protruding portions composing lips free to flex, and a fastening element upstanding from the inner face of the other of said parts of the 5 aforesaid body, said fastening element having a rigid loop portion adapted to be forced in the slot so that the lips will snap past it.

JAMES WILLIAM HUTT. 10
